UNITED STATES PATENT OFFICE.

JOHN F. BUTZ, OF FORT WORTH, TEXAS.

MARINE PUZZLE OR TOY.

SPECIFICATION forming part of Letters Patent No. 628,520, dated July 11, 1899.

Application filed July 15, 1898. Serial No. 685,997. (No model.)

To all whom it may concern:

Be it known that I, JOHN F. BUTZ, of Fort Worth, Tarrant county, Texas, have invented certain new and useful Improvements in Marine Puzzles or Toys, of which the following is a specification.

My invention relates to marine puzzles or toys; and it consists in certain novel and peculiar features of construction and combinations of parts, as will be hereinafter described and claimed.

The object of the invention is to produce a toy or puzzle consisting, essentially, of a tank containing water, two fleets of miniature war vessels, representing, for instance, the Spanish fleet at Manila and the American fleet at the same place, and means whereby the former are sunk through the instrumentality of one or more of the latter.

In order that the invention may be fully understood, I will proceed to describe it with reference to the accompanying drawings, in which—

Figure 1 represents a perspective view of a puzzle or toy embodying my invention. Fig. 2 is an inverted plan view, partly in side elevation and partly in section. Fig. 3 is a vertical longitudinal section. Fig. 4 is a perspective view of a part of the ship-supporting partition or diaphragm.

In the said drawings, 1 designates a tank or receptacle of elliptic or any other preferred configuration, and 2 a horizontal partition or diaphragm therefor, said partition or diaphragm being supported in a horizontal position in the tank by the arms 1^a, formed with or secured to the tank proper by preference. The partition or diaphragm is provided, preferably near its center, with a plurality of openings 3, approximating the configuration of a vessel, and in order that an extended bearing may be provided I prefer that these openings shall be stamped in metal with marginal flanges 4 projecting upwardly. The partition or diaphragm is also provided with an equal or greater number of small perforations 5. A flexible plate 6 extends at right angles to each opening 3, which in this instance equal the number of Spanish ships engaged in the naval engagement off Manila, and said plates at their outer ends preferably are secured to the under side of the partition

or diaphragm by means of rivets 7 or their equivalents and at their inner ends, as at 8, underlap slightly the openings 3, being supported in such position by means of the guide-clips 9, secured to the under side of the partition.

10 designates a number of vessels representing the Spanish fleet, fitting in the flanged 60 openings 3 and initially resting upon the resilient plates 6.

11 designates a number of vessels representing the American fleet, and said vessels rest squarely upon the partition or diaphragm 65 2, and at least one of them is provided with a vertical pin 12, extending downward through a registering opening 5, care being taken that the partition or diaphragm is provided with at least one opening vertically over each resilient plate 6.

When the vessels are arranged as described, water is poured into the tank until the partition is completely submerged, and this water may be tinted blue or green to make the 75 representation appear more natural and also to render it difficult or impossible to locate the perforations of the partition.

In order to "do as Dewey did"—that is, to sink the Spanish fleet—one of the American 80 vessels, provided with a depending pin 12, is grasped, as illustrated in Fig. 1, and the operator seeks to locate with the pin 12 the opening 5 registering with the resilient plates 6 of a particular Spanish vessel. When this 85 is accomplished, the operator presses down upon said plate, as indicated in Fig. 3, and by bending the same withdraws or slides its free end from under the vessel referred to, which, of course, drops down through the 90 opening 3. In most instances the vessel will sink down in an upright position, leaving exposed to view only the mast, but sometimes the vessel will sink with bow or stern projecting up through the opening and above the 95 surface of the water. As it would add to the realistic effect to have the vessels sink in different positions, it can be accomplished by simply permitting the vessels more play in the openings 3, or it may be accomplished by 100 increasing the weight of one end of the vessel. This, however, is immaterial. To sink the remaining vessels, the operation as described is repeated. In Fig. 5 six of the

Spanish vessels are still afloat and the American flagship is being positioned to sink one of them. When the vessels are reëlevated, the plates 6 instantly resume their original position in order to maintain the vessels in their elevated position, as will be readily understood.

It is preferred that the depth of the tank be such as to always leave the masts of the vessels projecting above the surface of the water in order that they may be reëlevated without necessitating the removal of the partition or of the water; but in order to remove the latter conveniently it is provided with a drain-cock 13 of the type shown or of any other suitable or preferred type.

While I have illustrated and described only a single method of supporting the vessels and of withdrawing the supporting-plates from beneath the same, it is to be understood that the same object may be accomplished in many different ways without departing from the essential spirit and scope of my invention.

Having thus described the invention, what I claim as new, and desire to secure by Letters Patent, is—

1. A puzzle or toy, comprising a tank provided with a substantially horizontal partition or diaphragm having an opening, a suit-

ably-supported resilient plate underlying said partition or diaphragm and said opening, and adapted to support an object in and above the latter, and means to bend said support and thereby slide it from under said opening, substantially as described.

2. A puzzle or toy, comprising a tank provided with a partition or diaphragm containing small openings and relatively large openings, resilient plates arranged at the under side of said partition or diaphragm, having their outer ends anchored or secured immovably and their inner ends occupying positions in alinement with the large openings, guide-clips embracing said plates near their free ends to insure a sliding longitudinal movement thereof, and a ship provided with a depending pin or stem for insertion through one or another of the small openings and engagement with the plate below in order to bend the same and thereby withdraw it from alinement with the corresponding large opening, substantially as described.

In testimony whereof I affix my signature in the presence of two witnesses.

JOHN F. BUTZ.
